(57) **CLAIM**

The ornamental design for an electric prong adaptor, as shown and described.

DESCRIPTION

FIG. 1 is a front view of a first preferred embodiment of an electric prong adaptor constructed in accordance with the present invention shown inserted in an electrical outlet receptacle with the receptacle shown in dashed lines;

FIG. 2 is a perspective view of the electric prong adaptor shown in FIG. 1;

FIG. 3 is a top view of the electric prong adaptor shown in FIG. 1;

FIG. 4 is a rear view of the electric prong adaptor shown in FIG. 1;

FIG. 5 is a left side view of the electric prong adaptor shown in FIG. 1 (the right side view being a mirror image thereof);

FIG. 6 is a bottom view of the electric prong adaptor shown in FIG. 1;

FIG. 7 is a front view of a second preferred embodiment of an electric prong adaptor shown inserted in an electrical outlet receptacle with the receptacle shown in dashed lines;

FIG. 8 is a perspective view of the electric prong adaptor shown in FIG. 7;

FIG. 9 is a top view of the electric prong adaptor shown in FIG. 7;

FIG. 10 is a rear view of the electric prong adaptor shown in FIG. 7;

FIG. 11 is a left side view of electric prong adaptor shown in FIG. 7;

FIG. 12 is a bottom view of the electric prong adaptor shown in FIG. 7; and,

FIG. 13 is a right side view of the electric prong adaptor shown in FIG. 7.

In FIGS. 1 and 7, the broken lines depict unclaimed subject matter only and form no part of the claimed design.

1 Claim, 4 Drawing Sheets
